UNITED STATES PATENT OFFICE.

ABRAHAM S. ISERSON, OF NEW YORK, N. Y.

STATIONARY ELECTRIC-IRON HEATER.

1,217,000.

Specification of Letters Patent. Patented Feb. 20, 1917.

Application filed September 9, 1916. Serial No. 118,247.

To all whom it may concern:

Be it known that I, ABRAHAM S. ISERSON, a citizen of the United States, and a resident of the city of New York, borough of Manhattan, in the county and State of New York, have invented a new and Improved Stationary Electric-Iron Heater, of which the following is a full, clear, and exact description.

This invention relates to electric flat irons and has particular reference to means to facilitate the use of such irons.

Among the objects of the invention, therefore, is to provide an electric connection for a flat iron which will be independent of the iron when the iron is in actual use for laundrying purposes, thereby making the iron free and independent from all mechanical obstructions which tend to interfere with the free use thereof.

Another object of the invention is to provide a stationary support to receive the iron while it is being heated, said support constituting the means to which the electric wires are attached and also being provided with suitable contacts to bring the iron heater into action when the iron is supported upon the support substantially the same as if the electric wires were connected directly and permanently to the iron.

A further object of the invention is to provide a safety switch within the support so arranged as to be automatically thrown out to break the circuit through the exposed contacts when the iron is lifted from the support, but which is again thrown in to complete the circuit by the physical contact of the iron when the iron is returned to the support for reheating.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a vertical central longitudinal section on the line 1—1 of Fig. 2;

Fig. 2 is a plan view;

Fig. 3 is a view similar to Fig. 1, but with

the iron removed and the automatic switch thrown to its opposite position;

55

Fig. 4 is a vertical transverse section on the line 4—4 of Fig. 3; and

Fig. 5 is a diagram indicating the electric circuit and its connections.

Referring now more particularly to the drawings, I show a flat iron support 10 of any suitable size or design and comprising a flat top 11 of slate, soapstone or any other suitable material upon which the smooth bottom surface of the flat iron 12 is adapted to rest while the iron is being heated. The slab 11 is built upon a base 13 of suitable structure providing for a hollow center 14, in which the electric connections or controlling devices are mounted, and access to which may be had through the open bottom of the base. It will be understood that the support 10 may be of sufficient weight to maintain it in suitable position at any convenient place adjacent the operator's table or ironing board, which said support may be anchored in any suitable manner to the table or other point of support, but which support may be regarded as stationary in the practical operation of the invention.

80

The iron is or may be substantially similar to electric irons as now commonly found on the market, but for the purpose of the present disclosure, I show the flat iron comprising a heat retaining base 15, in connection with which is provided a rheostat or heater 16 having opposite terminals 17 and 18 for the electric connections.

85

In accordance with the usual practice of electric irons, the feed wires 19 and 20 are run into the body of the iron and permanently secured to the contacts 17 and 18. Under these circumstances, the wires must necessarily follow the movements of the iron and cause much inconvenience and annoyance to the user of the iron.

95

In accordance with my invention, the feed wires are connected permanently to or in the base 13 of the support and are thence extended upwardly through a hole 21 in the slab 11 where they are severally connected to the spring contacts 22 and 23. These spring contacts are insulated from each other and from a guard 24 having flexible connection at 25 with the top of the slab or support. This flexibility provides for the ac-

100

105

commodation of flat irons of slightly different lengths and also insures that proper engagement will be made between the heater contacts 17 and 18 carried by the iron and the spring contacts 22 and 23 with which said heater contacts are adapted to engage respectively when the iron is supported upon the slab for the purpose of being heated.

So far as the invention is now described, 10 it will be seen that when the iron is placed upon the support, resting longitudinally between the contacts 22 and 23 at one end and the V-shaped guard 26 at the other end and supported also from lateral displacement by corner brackets 27, the feed wires 19 and 20 will be electrically connected through the heater 16 with precisely the same effect upon the heater as though the feed wires were connected directly and permanently to said heater. Furthermore, 15 when the iron is heated and lifted from its support, the circuit will be broken between the feed wires at the contacts 22 and 23. The iron will thus be free for such manipulation as it is intended for and will retain 20 the heat in the base 15 for a considerable length of time, depending, of course, upon the weight of the goods being pressed. I have found in practice that after the iron 25 is once heated, it will be kept in proper operating condition, receiving its additional heat while resting upon the support during the times that the operator is placing or arranging the goods for the pressing 30 operation. It will thus be seen that I provide an electric heater having all the advantages of the electric heaters commonly used, but with none of their disadvantages. In other words, the iron according to this 35 invention is used substantially the same as though it were being heated upon a hot stove or the like, being entirely free for manipulation when lifted from the stationary support.

40 The guard 24 extending well over the contacts 22 and 23 makes it reasonably safe for the operator against receiving a shock, but I prefer to use an automatic switch, as indicated at 28, within the cavity 14 of the support. Said switch is shown as of a knife blade type pivoted at 29 and acted upon by a spring 30 tending to throw the switch blade out of contact with the spring contacts 31 connected respectively to the feed 45 wires. A pin 32 projects vertically through a hole 33 in the slab 11 and bears at its inner end upon the opposite end 28' of the switch blade. The length of the pin 32 is such that when the iron is placed upon the slab, the pin will be forced downwardly causing the switch blade 28 to come between the contacts 31 and close the circuit at this point, the weight of the iron being sufficient for 50 this purpose. Hence, so long as the iron 55 remains in its heating position, the circuit

will be completed through the contacts 31, as well as through the contacts 22 and 23. When, however, the iron is lifted, the spring 30 breaks the contact at the points 31 and thus the then exposed contacts 22 and 23 become dead and thoroughly safe from any likelihood of shocking the operator.

I indicate at 34, a fuse which may be used, if desired, to prevent the danger of short circuiting and I also indicate at 35 a manually operated switch for turning on or off the circuit for the convenience of the operator. This switch 35 also constitutes an indicator whereby the operator will always know at a glance whether the current 60 is on or off. Under those circumstances when the iron would otherwise become too hot while supported in heating position, it may be rested on any other support or placed transversely of the slab 11 out of 65 contact with the contact springs 22 and 23. In this position, even though the pin 32 is depressed, the circuit remains broken at the spring contacts.

I claim:

1. The herein described electric iron support comprising a stationary base to directly receive and support the iron, a pair of feed wires extending into and upwardly through the base, a pair of contacts for the respective wires, a guard extending over said contacts to protect the operator, said contacts being secured to the guard, and flexible means connecting the guard and the contacts to the support base.

2. The herein described electric iron support comprising a stationary base, a pair of feed wires extending upwardly through the base adjacent one end thereof, a pair of contacts connected to the ends of the 105 wires, a guard extending beneath and over the contacts, the contacts being rigidly secured to the lower portion of the guard, a fixed guard at the other end of the base, and resilient hinge means connecting the first 110 mentioned guard to the base providing for a slight variation in distance between the two guards according to the various lengths of irons used in connection with the support.

3. In an electric iron support, the combination of a rigid base having a flat horizontal upper surface upon which an iron is adapted to be placed by direct downward movement, a fixed guard for one end of the 115 iron, a resiliently supported guard for the other end of the iron, a pair of contacts fixed to one of said guards, a pair of circuit wires leading to said contacts, a movable switch below the horizontal supporting base, 120 means acting upon the switch tending to break the circuit through said wires, and a vertically reciprocating pin movable through the central portion of the base and depressible by the weight of the iron when the iron 125 130

is lowered into supported position to move the switch to closed position.

4. The herein described electric iron support comprising a stationary base, a pair of 5 spring contacts carried by the base, feed wires leading through the base to said spring contacts, and a switch within the base below the supporting surface thereof serving to make or break the current through 10 said feed wires.

5. The combination with a pressing iron having electric heating coils therein and two exposed terminals for the coils, of a stationary support to receive and hold the iron

during the heating operation, a pair of contacts carried by the support and adapted to engage said terminals respectively, feed wires leading through said support to the contacts, a switch serving to complete the circuit through said wires automatically 15 when the iron is put in place upon the support, and means to throw out said switch when the iron is lifted. 20

ABRAHAM S. ISERSON.
